UNITED STATES PATENT OFFICE

161,610

ICED CAKE

Edward Brenner and Hymie Brenner,
Arlington, Va.

Application April 21, 1950, Serial No. 9,395

Term of patent 14 years

(Cl. D8—1)

To all whom it may concern:

Be it known that we, Edward Brenner and Hymie Brenner, both citizens of the United States, and residing at Arlington, in the county of Arlington, State of Virginia, have invented a new, original, and ornamental Design for an Iced Cake, of which the following is a specification:

Reference is had to the accompanying drawing, forming a part of the instant application, in which

Fig. 1 is a plan view of the iced cake; and
Fig. 2 is a left end view thereof.

We claim:

The ornamental design for an iced cake, as shown.

EDWARD BRENNER.
HYMIE BRENNER.
